J. B. YOUNG.

Door Bell.

No. 11,236.

Patented July 4, 1854.

Fig. 1.

Fig. 2.

UNITED STATES PATENT OFFICE.

JEROME B. YOUNG, OF HARPERS FERRY, VIRGINIA.

MODE OF HANGING BELLS.

Specification of Letters Patent No. 11,236, dated July 4, 1854.

To all whom it may concern:

Be it known that I, JEROME B. YOUNG, of Harpers Ferry, in the county of Jefferson and State of Virginia, have invented and 5 made certain new and useful Improvements in Bells; and I do hereby declare that the following is a full, clear, and exact description of the method of construction and mode of operating the same, reference being had 10 to the accompanying drawings, and making a part of this specification, in which—

Figure 1, is a view of the bell complete, attached to a door (for which the improvement is principally designed), and showing 15 the lever handle of the bell, which is attached to the screw G on the inside of the door. Fig. 2, shows section or fragment of the door rails A, with the bell B, B, B. The lever handle C, C, c, passing in the direction of the dots through the tube D, D; 20 the vertical pistons striker E, E, passing through the barrel or socket F, which is attached to the arm H, H, which has a screw thread C, to which is attached the bell 25 B, B, B.

To enable others to be skilled in the use and application of my invention and improvements, I will proceed to describe the construction and operation thereof, the nature and principles of which, consist in constructing a door or signal bell, in the form of a bowl or dish like shape, indicated by B, B, B, Fig. 2, of any required size, and attaching the same by a female screw and a male screw G formed on the end of an arm H, H, formed on the end of a cylindrical tube D, D, having an actuating lever C, C, c, passing through the tube D, in the form indicated by the dots. The fulerum S, of the 30 lever being nearer the larger or handle end C, c, Fig. 2. The said tube D, D, is inserted in the middle rail or strip of the front door of a dwelling, as in Fig. 1. This rail has a hole of the required size cut into it, sufficiently large to admit of a neat and close fitting of the tube therein. On the inside 35 end of this tube, is formed an elbow and arm H, H; on the top of which is a barrel or socket F, through which passes and in which 40 works a detached piston like gravitating striker E, E, of steel or iron. The lower end of this striker rests on the small end of

the actuating lever C, C, c, when at rest. The bell B, B, B, being attached to the screw G, completes the whole device; which 55 is designed principally to be used as a front door bell but which may be used in other ways and for other purposes.

The utility of my system of door bells is most obvious. First, because of the cheapness and simplicity of construction of the bell. Secondly, the non-liability to get out of order; the usual wires, cranks, &c., being entirely dispensed with. Thirdly, the ready 60 action of the bell, and sonorous, distinct 65 sound afforded, which arises in part, from the fact, that the door to which the bell is attached, acts as a sounding or reverberating medium; thus rendering the signal or alarm prompt and effectual.

The method of operating the same is simple, and is readily understood at a glance by reference to diagrams, Figs. 1, 2. The outside or handle end C, c, is struck or pressed down by the fingers or hand; which depression of the handle, lifts or throws up the striker E, E, which being within the concavity of the bell, and having sufficient room or play, strikes upward, against the inner circumference; thus producing the signal or 80 sound. The striker E, E, being confined within the socket, can not by any ordinary means get out of place.

Having thus fully represented my improved bell by drawings, and described the 85 construction thereof, what I claim as new, and desire to secure by Letters Patent of the United States, is as follows:

I claim the construction of a bell having attached thereto, an arm H, H, formed on a 90 tube D, D, having working through it, an actuating lever C, C, c, combined with a gravitating piston striker E, E, working through a barrel or socket F, attached to the elbow and arm H, H, the whole used together with the tympanum B, B, B, and combined in its application with the door of a dwelling, or otherwise, substantially as set forth.

JEROME B. YOUNG.
